PANTS TOPPER

Fred F. Littell, Pico, Calif.

Application May 25, 1946, Serial No. 672,280

12 Claims. (Cl. 223—73)

1

This invention relates to a pants topper or to a device for pressing the upper portion of a pair of pants.

It is now conventional practice to employ for the pressing of the upper portion of a pair of pants that has been cleaned a pants topper which is similar in construction and operation to the steam presser used to press the creases in the pants legs. In the use of such pants toppers the upper portion of the pair of pants is slipped onto the support of the pants topper and a steaming and pressing platen is lowered thereagainst. The use of such pants toppers is objectionable (1) because the operation is comparatively slow; (2) the operation tends to contribute to the shine on the fabric; and (3) where there are several thicknesses of fabric such as those thicknesses created by the presence of pockets and adjacent the fly these thicknesses are accentuated on the obverse side of the fabric for if there are any undesirable creases in the upper portion of the pair of pants the pants topper may tend to set these creases therein.

In pressing the upper portion of a pair of pants it is desirable to have the fabric smooth and uncreased except where the pants has incorporated therein pleats adjacent the waistband. The usual procedure is to first press the upper portion of the pants and to thereafter press the leg portions forming the creases therein which terminate at or about the level of the crotch. This operation is performed on a pressing machine of adequate length and on which the pants are positioned after having been topped.

An object of the present invention is to provide an improved pants topper which is so constructed that the top of a pair of pants may be pressed much more rapidly without contributing to the shine of the fabric and without causing the presence of several layers of fabric such as the pockets or fly or buttons to be accentuated through the fabrics to be noticeable on the obverse side thereof.

More specifically, an object of the invention is to provide a method and apparatus for topping pants consisting of a throat over which the belt or waistband of the pants may be positioned and from which extend spaced steam discharge pipes adapted to enter the upper portions of the pants legs. Steam is discharged through these steam pipes to steam the fabric of the pants and thereafter the steam is turned off and a strong blast of air is discharged through the throat and into the pants holding the upper portion of the pants in a fully distended position, causing the fabric to

2

dry while in this inflated or distended condition. In this manner a pair of pants to be topped may be easily and quickly applied to the throat, steamed, and dried while in this inflated or extended condition with the result that no shine to the fabric is imparted thereto and the underlying pockets and the like do not tend to protrude through the fabric and become noticeable on its obverse side.

10 Another object of the invention is to provide a method and apparatus having the above-mentioned characteristics which has an adjustable means that may be optionally employed to set and maintain pleats adjacent the belt or waistband in the event that the pants have such pleats thereon.

With the foregoing and other objects in view, which will be made manifest in the following detailed description and specifically pointed out 20 in the appended claims, reference is had to the accompanying drawings for an illustrative embodiment of the invention, wherein:

Figure 1 is a view in side elevation of the apparatus embodying the present invention, parts 25 being broken away and illustrating a pair of pants in applied position thereon;

Fig. 2 is a top plan view of a portion of the apparatus shown in Fig. 1, the pants not being illustrated;

Fig. 3 is a view in front elevation of the upper portion of the apparatus illustrated in Fig. 1, and 30 may be regarded as having been taken in the direction of the arrow 3 upon Fig. 2;

Fig. 4 is a sectional view taken substantially upon the line 4—4 upon Fig. 2;

Fig. 5 is a sectional view taken substantially upon the line 5—5 upon Fig. 3, illustrating the details of construction employed to set and maintain the pleats;

Fig. 6 is a sectional view through a portion of the mechanism illustrated in Fig. 5;

Fig. 7 is a partial view in vertical section taken substantially upon the line 7—7 upon Fig. 5; and

Fig. 8 is a partial view in vertical section taken substantially upon the line 8—8 upon Fig. 7.

Referring to the accompanying drawings wherein similar reference characters designate similar parts throughout, the improved pants topper comprises a suitable housing 10 within which there is a motor driven blower 11 driven by an electric motor 12 or the equivalent and which discharges air through a duct 13. The flow of air through the duct is controlled by means of a damper 14 and when the damper is open 50 the air discharges at relatively high velocity and

in considerable volume through a throat 15 in the side of the housing. This throat is preferably equipped with a flexible fabric skirt 16. The damper 14 is preferably urged into a normal closed position such as by a tension spring 17 but may be opened by means of a treadle 18 mounted on the front of the housing and connected to the damper such as by a cable or chain 19. Thus by depressing the pedal or treadle 18 the damper may be swung into open position to allow air from the blower 11 to be discharged through the throat 15 and on release of the pedal 18 the damper will be automatically returned to closed position.

A pair of steam discharge pipes 20 and 21 project forwardly adjacent the throat 15 and preferably slightly diverge from each other. These steam discharge pipes are of sufficient length as to enter the legs of the average size of a pair of pants P. These steam discharge pipes consist of perforated pipes 22 at opposite sides of which there are preheating imperforate pipes 23 which serve to heat the steam discharge pipes and prevent the collection of condensate therein. The steam discharge pipes are supplied with dry steam through a conduit 24 leading from a steam separator 25 controlled by a valve 26 that is normally urged into closed position but which may be opened by a pedal or treadle 27 connected thereto as by a cable or chain 28. The preheating pipes 23 may be supplied with steam from the steam separator 25 such as by a conduit 29. The steam separator is supplied with steam from any suitable source through piping or tubing 30 and the steam which is supplied to the preheating pipes 23 may be returned to this source such as by a return pipe 31.

In the use of the apparatus as above described, a pair of pants that is to be topped is slipped over the steam discharge pipes 20 and 21 so that these pipes enter the legs of the pants. The belt or waistband of the pants is moved rearwardly to be positioned over the throat or adjacent the throat and steam is released through the valve 26 by depressing the pedal 27. As soon as pants have been adequately steamed the pedal 27 is released cutting off further discharge of steam and the pedal 18 is depressed opening the damper 14 and allowing a large volume of air at relatively high velocity to be discharged into the upper portion of the pants. This air tends to inflate the fabric skirt 16 against the interior of the pants to prevent the escape of air out of the top thereof. The volume and velocity of air are such as to inflate or distend the upper portion of the pair of pants. As the pants legs taper downwardly they form relatively restricted outlets for the air so that the upper portion or pants tops will be maintained in this distended condition. A substantial portion of the air is forced outwardly through the fabric in the top of the pants drying the fabric thoroughly while in this distended condition. As soon as the fabric has become thoroughly dry the pants topping operation is completed and the pants may then be pressed on the leg-pressing machine in the conventional manner to set the creases in the pants legs.

While I have employed a bag surrounding the steam discharge pipes 20 and 21 and which is connected to the throat 15 designed to have the pants P slipped thereover I find that the use of such bag is unnecessary and sometimes objectionable in that it interferes with the application of the pants to the machine and detracts

from the ability to fully inflate the top of the pants. Consequently in the preferred form of construction the bag is entirely eliminated and only the skirt 16 employed to prevent leakage between the throat and the top of the pants. By pressing the pants top in this manner no shine is imparted to the fabric and underlying objects such as pockets or buttons are not pressed through the fabric so as to be noticeable on the obverse side.

In order to set and press pleats in the top of the pants an arcuate member 32 is mounted on the housing 10. This arcuate member has a pair of supports 33 laterally adjustable thereon. Each support preferably consists of a perforated plate mounted on a longitudinally extending arm 34 recessed on its underside to accommodate the upper portion of the arcuate member and having secured thereto an auxiliary arm 35. The two arms are bolted together such as by bolts 36 and have anti-friction bearings such as balls 37 engageable with the arcuate member to facilitate lateral adjustment. Each support 33 has in opposite thereto a presser member 38 in the form of a perforated plate which can be swung downwardly by means of a hollow handle 39 pivoted as at 40 to the auxiliary arm 35. A quadrant 41 is pivoted to the auxiliary arm as at 42 and extends through an opening in the handle 39. This quadrant presents a serrated edge as indicated at 43 engageable by a ratchet member 44 that can be forced into engagement with the teeth on the quadrant by means of a rod 45 having threads 46 meshing with threads on the interior of the handle 39. A grip 47 is mounted on the rod 45 and on turning the rod by means of the grip the ratchet 44 may be advanced into engagement with the quadrant 41 on release therefrom. The handle 39 has a tubular extension 48 into which the stud 49 on the presser member 38 slidably extends. This stud is urged downwardly by means of a compression spring 50.

If the pants P has pleats adjacent its belt or waist band the supports 33 are laterally adjusted on the arcuate member 32 so as to be positioned beneath the pleats. The pants are then slipped on to the steam discharge pipes 20 and 21 and the pleated portions are positioned over the supports 33. The pleats, one of which is indicated at L on Fig. 7, are then manually set in the fabric and on being set the presser members 38 are swung downwardly from the dotted line position shown in Fig. 5 to the full line position and pressed firmly against the top of the pleat. The compression spring 50 may be compressed slightly during this operation and the grip 47 is then rotated to advance the ratchet 44 into engagement with the teeth 43 locking the presser member 38 in pressing position over the pleat L. The steam is then discharged through the steam discharge pipes 20 and 21 and may pass through the pleated portion of the pants top by virtue of the perforations in the supports 33 and in the presser members 38. When the fabric is well steamed the steam may be turned off by releasing the pedal 27 and air discharged through the throat 15 as previously described. If the pants are not provided with pleats the presser member 38 and the handle 39 may be left in the fully open or dotted line position illustrated in Fig. 5.

From the above-described construction it will be appreciated that an improved method and apparatus for topping pants is provided which is highly advantageous over the pressing methods

and machines now in general use. I find that a single operator employing a machine of this character may top pants at a rate to supply topped pants to two operators operating pressing machines for pressing the pants legs. By using the pants topers now in general use due to the number of different settings of the pants and the time required a very efficient pants topper is just capable of topping the pants that a single pants-leg presser may press. The construction is not only highly advantageous in the time and labor saved but is advantageous in that the pants will be smooth and any creases in the tops will be automatically removed due to the fact that the steamed tops are dried while in an inflated or extended condition. Likewise, there are no marks or noticeable protuberances of underlying objects such as pockets or buttons.

Various changes may be made in the details of construction without departing from the spirit and scope of the invention as defined by the appended claims.

I claim:

1. The method of top pressing a pair of pants which consists of discharging steam into the interior of the pants near the top thereof and thereafter discharging air through the top of the pants toward the legs with sufficient volume and velocity to cause the air to hold the top of the pants distended while being dried.

2. The method of top pressing a pair of pants which consists of setting the pleats if any in the top of the pants by pressing them between perforated pleat holders, discharging steam into the top of the pants, and then discharging air through the top of the pants toward the legs with sufficient volume and velocity so as to fully distend the top and hold it distended while drying.

3. A pants topper comprising means providing a throat, a pair of spaced steam discharge pipes projecting forwardly from the throat adapted to have the pants legs of a pair of pants positioned thereon, means for discharging steam through the steam discharge pipes, and means for discharging air through the throat with sufficient velocity and volume to distend the top of the pants.

4. A pants topper comprising means providing a throat, a pair of spaced steam discharge pipes projecting forwardly from the throat adapted to have the pants legs of a pair of pants positioned thereon, means for discharging steam through the steam discharge pipes, means for discharging air through the throat with sufficient velocity and volume to distend the top of the pants, and a skirt around the throat adapted to be expanded by the air into engagement with the interior of the pants.

5. A pants topper comprising means providing a throat, a pair of spaced steam discharge pipes projecting forwardly from the throat adapted to have the pants legs of a pair of pants positioned thereon, means for discharging steam through the steam discharge pipes, means for discharging air through the throat with sufficient velocity and volume to distend the top of the pants, and perforated supports adjacent the throat extending forwardly therefrom, and cooperating pleat-setting members for clamping a set pleat thereagainst.

6. A pants topper comprising means providing a throat, a pair of spaced steam discharge pipes projecting forwardly from the throat adapted to have the pants legs of a pair of pants positioned thereon, means for discharging steam through the steam discharge pipes, means for discharging

air through the throat with sufficient velocity and volume to distend the top of the pants, and perforated supports adjacent the throat extending forwardly therefrom, and cooperating pleat-setting members for clamping a set pleat thereagainst, said supports and pleat-setting members being adjustable about the top of the throat.

7. The method of topping pants which consists of steaming the fabric of the pants and then discharging air through the pants from the waist band toward the ends of the pants legs with sufficient volume and velocity so that although the air may escape through the ends of the pants legs the fabric of the pants will be fully distended adjacent the waist band and dried by the air while in this condition.

8. The method of topping pants which consists of discharging steam into direct contact with the interior of the fabric of the pants adjacent the waist band and in the pants legs and thereafter discharging air through the pants from the waist band thereof toward the ends of the pants legs with sufficient volume and velocity so that although the air may escape from the ends of the pants legs the pants at least adjacent the waist band will be inflated and distended thereby and dried by the air while thus inflated.

9. A pants topper comprising means providing a throat over which the waist band of a pair of pants may be slipped, a pair of perforated steam pipes projecting from the throat arranged to extend into the pants legs of the pants, means for discharging steam through said steam pipes to be discharged thereby into direct contact with the interior of the pants, and means for discharging air through the throat with sufficient volume and velocity to inflate the pants at least adjacent the waist band even though the air may escape through the ends of the pants legs.

10. A pants topper comprising means providing a throat over which the waist band of a pair of pants may be slipped, a pair of perforated steam pipes projecting from the throat arranged to extend into the pants legs of the pants, means for discharging steam through said steam pipes to be discharged thereby into direct contact with the interior of the pants, means for discharging air through the throat with sufficient volume and velocity to inflate the pants at least adjacent the waist band even though the air may escape through the ends of the pants legs, and means for forming a seal against the escape of air between the throat and the interior of the pants adjacent the waist band.

11. A pants topper comprising means providing a throat over which the waist band of a pair of pants may be slipped, a pair of perforated steam pipes projecting from the throat arranged to extend into the pants legs of the pants, means for discharging steam through said steam pipes to be discharged thereby into direct contact with the interior of the pants, means for discharging air through the throat with sufficient volume and velocity to inflate the pants at least adjacent the waist band even though the air may escape through the ends of the pants legs, supports adjacent the throat adapted to be positioned within the pants when the pants are applied to the throat, and means adapted to cooperate with said supports for pressing a pleat or pleats in the pants adjacent the waist band.

12. The method of topping pants which consists in gripping the pants at the waist portion thereof, discharging steam into direct contact

with the interior of the fabric of the pants adjacent to the waist band and in the pants legs, creating a blast of air having a cross sectional area approximately the size of the waist opening of the pants, causing the blast of air to be directed into the throat of the pants in the direction of the pants legs through the pants legs and outwardly thereof, maintaining the blast of air at a volume and velocity such that the resistance of the air escaping through the pants legs is sufficient to create an air pressure in the pants to balloon the pants, continuing the blasts of air until the pants are dry, and then discontinuing the blast of air to allow the pants to collapse.
